UNITED STATES PATENT OFFICE.

LIONEL C. DE LEON, OF NEW ORLEANS, LOUISIANA.

DESIGN FOR AN EMBLEM, BADGE, OR BUTTON.

60,218.

Specification for Design.

Patented Jan. 17, 1922.

Application filed August 29, 1921. Serial No. 496,713. Term of patent 3½ years.

To all whom it may concern:

Be it known that I, LIONEL C. DE LEON, a citizen of the United States, residing at New Orleans, in the parish of Orleans, State of Louisiana, have invented a new, original, and ornamental Design for an Emblem, Badge, and Button, of which the following is a specification, reference being had to the accompanying drawing, forming a part thereof.

The figure is a plan view of an emblem, badge or button, showing my new design. The words "Master Plumbers" constitute a part and parcel of the artistic and ornamental design for emblems or badges.

I claim:—

The ornamental design for an emblem, badge or button, as shown.

LIONEL C. DE LEON.
